UNITED STATES PATENT OFFICE

EMMOR H. KELLEY AND GEORGE A. STEWART, JR., OF SOUTH BROWNSVILLE, PENNSYLVANIA.

PORTABLE CRANE.

1,416,958.

Specification of Letters Patent. Patented May 23, 1922.

Application filed February 5, 1921. Serial No. 442,854.

To all whom it may concern:

Be it known that we, EMMOR H. KELLEY and GEORGE A. STEWART, Jr., both citizens of the United States, and residents of South 5 Brownsville, in the county of Fayette and State of Pennsylvania, have invented certain new and useful Improvements in Portable Cranes, of which the following is a specification.

10 This invention relates to cranes of the portable type.

An important object of this invention is the provision of a portable crane especially adapted for use in removing the wheels of 15 vehicle trucks in such a manner that the bearings of the wheels will not be damaged in any way.

A further object of the invention is to provide a portable crane especially adapted 20 for removing vehicle wheels from trucks and provided with means whereby the same may be adjusted for use in connection with wheels of various sizes.

The invention forming the subject matter 25 of this application aims also to provide a portable crane which may be easily operated by one man, thereby dispensing with the necessity of employing an attendant in applying and removing the heavy wheels of 30 a vehicle truck.

Other objects and advantages of the invention will be apparent during the course of the following description.

In the accompanying drawings forming a 35 part of this application, and in which like numerals are employed to designate like parts throughout the same;

Figure 1 is a side elevation of the improved crane in use,

40 Figure 2 is a rear elevation of the same, in use,

Figure 3 is a front end elevation of the crane in use,

45 Figure 4 is a fragmentary plan view of the crane,

Figure 5 is a detail sectional view through the lifting bar of the crane,

Figure 6 is a fragmentary perspective view of the standard of the crane,

50 Figure 7 is a detail sectional view through the standard of the crane, the view illustrating the anti-friction elements with which the lifting bar is engaged,

55 Figure 8 is a detail view taken on the line 8—8 of Figure 1,

Figure 9 is a detail sectional view illustrating one of the casters applied,

Figure 10 is a detail sectional view taken on the line 10—10 of Figure 1,

Figure 11 is a detail sectional view 60 through the arm of a lifting bar.

In the drawings wherein for the purpose of illustration is shown a preferred embodiment of the invention, the numeral 15 designates the base of the standard, and the 65 base comprises a pair of spaced parallel legs 16 having their forward portions provided with rollers 17. The rear portion of the base is provided with a pair of brackets 18 to which casters 19 are connected. The 70 casters 19 may be held in an adjusted or set position by means of pins 20 which may be inserted through registering openings 21 in the shanks of the casters and in the brackets 18. When the pins 20 are inserted through 75 the registering openings 21 the casters are so positioned that the crane when moved will travel in a straight line. Of course when it is desired to turn the crane for changing its direction of travel the pins 20 80 are removed, so that the attaching portions of the casters may rotate within the brackets. The legs 16 have their rear portions connected by a pair of spaced parallel transversely extending angle bars 23 to 85 which a standard generally designated by the numeral 25 is connected by means of rivets 26. As illustrated in Figures 1 and 4, the standard 25 includes four spaced parallel upstanding beams 27 which are T-shaped in 90 cross section. The beams 27 are arranged in pairs, and the pairs of beams are connected at their upper portions by a plate 28 and at their intermediate portions by a plate 29 arranged on the opposite sides of the beams. 95 Rivets or other suitable fastening devices are employed for connecting the plates 28 and 29 to the beams 27. The inwardly extending ribs 30 are connected by pairs of upper and lower plates 31 to which upper 100 and lower rollers designated by the numerals 32 and 33 respectively, are connected.

With reference to Figures 2 and 3, it will be observed that the standard is braced in its connection with the base by means of inclined brace straps 35, which are secured to the intermediate portion of the standard and to the end portions of the angle plates 23.

The transversely extending angle bars 23 are connected by a pair of angle bars 36 110

which constitute a base for a jack designated by the numeral 37, which jack is adapted for elevating a lifting bar generally designated by the numeral 38.

5 The lifting bar as illustrated in Figure 4, includes a pair of channel plates 39 having outwardly directed parallel flanges 90, with which the upper and lower rollers 32 and 33 contact so as to provide a sliding connection between the standard and the lifting bar. With reference to Figure 7, it will be observed that the axis of the lower roller 33 is arranged in a vertical plane in advance of the axis of the roller 32 so as to contact 10 with the forward flanges of the channel plates while the rollers 32 contact with the rear flanges of the channel plates 39. In this manner, the pull exerted on the horizontal lifting arm 91 is prevented from 15 causing the lifting bar to bind on the standard when an effort is made to elevate the same.

As illustrated in Figures 5 and 6 the channel plates 39 are arranged in spaced 20 parallel relation and have angle bars 42 connected to their opposed sides by means of rivets or the like, and the angle bars are in turn joined by spaced plates 43. The lower ends of one pair of angle bars 42 terminate 25 at the intermediate portions of the lifting bar 38 so as to define an opening within which the jack is received. The head of the jack contacts with a pair of transversely extending angle bars 44, which may be riveted to the opposed sides of the channel 30 plates at the upper end of the opening in the lifting bar.

As illustrated in Figure 5, the angle bars 42 at the forward side of the lifting bar 40 are bent intermediate their ends, and are joined with the intermediate portion of the lifting arm 91 so as to constitute a brace 46 for the same.

The lifting arm 91 includes a pair of 45 spaced angle bars to which a chain supporting plate 50 is connected. A lifting chain 51 which is adapted to be passed about the rim of a tire, is connected to the plate 50 and is adjustably connected to a second 50 plate 52 by means of a slot 53 which is adapted to selectively receive one of the links of the chain. The adjacent link of the chain contacts with the upper face of the plate 52 and therefore prevents the disconnection 55 of the chain with the plate 52. The plate 52 is slidable on the horizontal arm 91, and is provided with an adjusting bolt 54 which is passed between the angle rods of the arm and is provided with a nut 55 by 60 means of which the bolt 54 may be securely engaged with the rod for holding the same in an adjusted position.

In the operation of the improved crane, 65 the same is moved up to one side of a vehicle wheel so that the lifting arm 91 will

overhang the vehicle wheel as illustrated in Figure 1. The chain 51 is now passed beneath the rim of the wheel and is adjustably connected to the plate 52. The lifting bar 38 is now elevated by means of the jack 70 so that the wheel may be withdrawn from the axle. Ordinarily it requires several men to remove the wheels of a vehicle truck as such wheels weigh approximately 1,500 pounds. With the use of this invention one 75 man may remove the wheel without the possibility of in any way damaging the bearings or associated elements. When the wheel is withdrawn the crane may be moved to any suitable place and when it is desired to 80 again attach the wheel the crane is returned to its original position so that the wheel may slip onto the axle.

Having thus fully described the invention, what is claimed is:

85

1. A portable crane comprising a standard, a lifting member slidably carried thereby and inclusive of a pair of spaced side bars, said lifting member being provided with a pair of angle bars connected to said 90 side bars and having inwardly directed flanges constituting a contact element for the head of a jack.

2. A portable crane comprising a standard, a lifting member slidably associated 95 therewith and consisting of a pair of side members and means connecting the side members, said lifting member being provided with angle bars having inwardly directed flanges constituting a contact element 100 for the head of a jack, one side of said lifting member being open for the reception of a jack, and a base movably supporting said standard.

3. A portable crane comprising a standard, a lifting member slidably associated therewith and consisting of a pair of side members and means connecting the side members, said lifting member being provided with angle bars having inwardly directed flanges constituting a contact element 105 for the head of a jack, one side of said lifting member being open for the reception of a jack, and a base movably supporting said standard, said lifting member being 110 provided with a laterally projecting lifting arm having means for engaging an article to be elevated.

4. A portable crane comprising a mobile base, a standard carried thereby and inclusive of inwardly extending flanges constituting guides, a lifting member having channel plates provided with outwardly extending flanges slidably contacting with said first named flanges, a lifting arm connected 115 to said lifting member, and attaching means carried by said arm.

5. A portable crane comprising a mobile base, a standard carried thereby and inclusive of inwardly extending flanges consti- 130

- tuting guides, a lifting member having channel plates provided with outwardly extending flanges slidably contacting with said first named flanges, a lifting arm connected to said lifting member, attaching means carried by said arm, anti-friction elements carried by said standard and contacting with the outwardly directed flanges of said lifting member.
- 5 6. A portable crane comprising a base, a standard carried thereby and provided with beams having inwardly extending flanges, a lifting member inclusive of channel plates having outwardly directed flanges contacting with said first named flanges, pairs of upper and lower rollers carried by said standard and contacting with said second named flanges, and an arm connected to said lifting member.
- 10 7. A crane comprising a base, a standard carried thereby, and inclusive of upstanding beams having inwardly extending flanges, a lifting member inclusive of channel plates having outwardly directed flanges, upper rollers carried by said standard and contacting with the flanges of said lifting member, a second set of rollers arranged beneath said first named rollers, and engaged with
- 15 the flanges of said lifting member, said second named rollers being arranged in advance of the first named rollers, and a laterally projecting arm carried by said lifting member.
- 20 8. A crane comprising a standard, a lifting member slidably carried thereby, and inclusive of a pair of angle rods having their upper portions extended outwardly to constitute braces, and an arm connected to said lifting bar and to said braces.
- 25 9. A crane comprising a standard, a lifting member slidably carried thereby, and inclusive of a pair of angle rods having their upper portions extended outwardly to constitute braces, an arm connected to said lifting bar and to said braces, and a flexible element carried by said arm.
- 30 10. A crane comprising a standard, a lifting member slidably carried thereby, and inclusive of a pair of angle rods having their upper portions extended outwardly to constitute braces, an arm connected to said lifting bar and to said braces, a flexible element carried by said arm, and an elevating device for said lifting member.
